United States Patent Office

Des. 200,931
Patented Apr. 20, 1965

200,931

JUG

Roy C. Josephsen, Hillsdale, Joseph R. Tino, Clifton, and
Charles R. Fulcher, Bloomfield, N.J., assignors to W. R.
Grace & Co., New York, N.Y., a corporation of
Connecticut

Filed June 17, 1964, Ser. No. 80,444

Term of patent 14 years

(Cl. D58—5)

FIG. 1.

FIG. 3.

Des. 200,931

PAGE 2

FIG. 2.

FIG. 4.

FIG. 5.

FIG. 6.

FIGURE 1 is side view of a jug showing our new design;

FIGURE 2 is an end view thereof;

FIGURE 3 is a bottom plan view thereof;

FIGURE 4 is a top plan view thereof;

FIGURE 5 is a side view opposite that shown in FIGURE 1; and

FIGURE 6 is an end view opposite that shown in FIGURE 2.

The dominant features of our design reside in the portions shown in full lines.

We claim:

The ornamental design for a jug or the like, as shown and described.
